(57) **CLAIM**

The ornamental design for a charger cover, as shown and described.

DESCRIPTION

FIG. 1 is a front perspective view of a charger cover, showing my new design;

FIG. 2 is a front elevation view thereof;

FIG. 3 is a rear elevation view thereof;

FIG. 4 is a left elevation view thereof, the right elevation view being a mirror image;

FIG. 5 is a top plan view thereof, the bottom plan view being a mirror image; and,

FIG. 6 is a front perspective view thereof, shown in use. The even length dash-dash broken lines shown protruding through the upper circular opening in FIG. 6 depicts environmental subject matter that forms no part of the claimed design, while the remaining even length dash-dash broken lines in the drawings depict portions of the charger cover that form no part of the claimed design.

The broken lines consisting of uneven length dash-dot-dash lines in the drawings depict the boundary of the claimed invention and it is understood that the claim extends to the boundary that forms no part of the claimed design.
